UNITED STATES PATENT OFFICE.

CARL G. FALKNER, OF DAYTON, OHIO.

AUTOMATIC CONTROL DEVICE.

1,305,205.

Specification of Letters Patent. Patented May 27, 1919.

Application filed October 16, 1916. Serial No. 126,050.

To all whom it may concern:

Be it known that I, CARL GEORGE FALKNER, a citizen of the United States, residing at Dayton, in the county of Montgomery and State of Ohio, have invented certain new and useful Improvements in Automatic Control Devices, of which the following is a specification.

My invention relates to automatic non-repeat mechanism or operation-determining means by which the succeeding operation of a given mechanism is limited to a predetermined number of cycles.

The object of the invention is to simplify the structure as well as the means and mode of operation of such devices whereby they will not only be cheapened in construction but will be more efficient in operation, positive in action, accurate, easily and readily controlled, and unlikely to get out of repair.

A further object of the invention is to provide means whereby the mechanism may be readily and quickly set to determine different numbers of operations at the will of the operator.

A further object of the invention is to provide improved form of means for automatically disconnecting the driving and driven parts at the termination of a predetermined cycle of operations.

With the above primary and other incidental objects in view, as will more fully appear in the specification, the invention consists of the features of the construction, the parts and combinations thereof, and the mode of operation, or their equivalents, as hereinafter described and set forth in the claims.

Referring to the drawings, Figure 1 is a side elevation of the assembled apparatus shown in its normal or inactive position. Fig. 2 is the top plan view thereof. Fig. 3 is a front elevation thereof. Fig. 4 is a detail side elevation of the side opposite that shown in Fig. 1, showing the parts in operated position. Fig. 5 is a detail side elevation of the restoring means. Fig. 6 is a detail perspective view of the series of timing disks. Fig. 7 is a detail interior view of the driving clutch. Fig. 8 is a detail view of

the clutch arresting and releasing member. Fig. 9 is detail view of counter-operating means.

Like parts are indicated by similar characters of reference throughout the several views.

The apparatus forming the subject matter hereof was particularly designed for use in conjunction with cinematographic cameras, more particularly when employed for reproducing animated cartoons. It is to be understood, however, that it is not limited to use in conjunction with moving picture cameras but may be readily applied to other uses for controlling various mechanisms wherein it is desired to limit the cycle of operations to predetermined numbers. In the production of animated cartoons by the cinematographic process, a succession of pictures are taken in each of several positions of the moving object, the number to be taken in the different positions varying with the rapidity of the movement to be indicated. Thus in one position a single exposure will be made while in another position two, three, or four exposures may be necessary to successfully portray the movement. The present apparatus is designed to automatically control the number of successive operations or exposures by the operation of a single key or button. The apparatus as shown is such that one, two, three or four exposures may be successively made at the will of the operator. The apparatus is adapted to limit the operations to a predetermined number by automatically disconnecting the driving element at the end of the predetermined cycle.

Referring to the drawings, there is shown a main frame 1, in which are mounted two parallel shafts 2 and 3. The shaft 2 is journaled for rotation in the main frame 1 while the shaft 3 may be fixed. The shaft 2 constitutes the drive shaft for the controlled mechanism whether the same be a cinematographic camera or some other mechanism and carries a drive pulley 4 to be operatively connected by a belt or otherwise with a motor or other prime mover. It is obvious that a gear or other driver may

be substituted for the pulley. The pulley 4 is loosely journaled upon the shaft 2 and normally rotates thereon independent of the shaft under the influence of the driving 5 motor.

The pulley is provided with a laterally disposed peripheral flange 5 forming in the side of the pulley 4 a recess or chamber 6. Fixedly secured upon the shaft 2 within the 10 chamber or recess 6 is a driving head 7, the periphery of which is notched or recessed to form shoulders 8 and angularly arranged faces 9. Located adjacent to the driving head 7 and loosely mounted upon the shaft 15 2 is a clutch disk 10 carrying thereon a series of rollers 11 which extend within the chamber 6 intermediate the angular faces 9 of the driving head and the peripheral flange 5 of the pulley. These rollers 11 are 20 so arranged that they normally contact the inner surface of the flange 5 which rotates thereabout but are normally out of engagement with the faces 9 of the driving head, as indicated by dotted lines in Fig. 7. However, upon a slight rotation of the clutch 25 disk 10 forwardly the rollers 11, traveling concentrically about the inner surface of the flange 5, are brought into engagement with the angular faces 9 of the driving head and 30 are forced or wedged into tight engagement therewith, thereby causing the driving head to rotate in unison with the pulley 4.

The clutch disk 10 is advanced in relation with the shaft and driving head to project 35 the rollers 11 into engagement with the driving head and is held in advanced position by means of springs 12 seated in bores 13 in the shoulders 8 and inclosed within reciprocatory sleeves 14, one of which bears upon each 40 of the rollers 11 and tends to advance the rollers and the disk to engaging position. In lieu of the spring 12 inclosed within the sleeves 14, which directly engage the rollers 11, a spring 15 seated within a bore 16 in 45 the shoulder 8 and engaging a lug or ear 17 projecting from inner face of the clutch disk 10 may be employed, as shown in Fig. 7. The construction is such that the pulley 4 normally rotates loosely upon shaft 2 until 50 the clutch disk 10 is released for its initial or engaging movement under the influence of the springs 12 or 15 according to the construction employed, whereupon the driving head 7 and pulley are interengaged one with 55 the other and the shaft 2 is rotated in unison with the pulley.

Located in parallel spaced relation upon the shaft 3 is a series of setting elements or operation-determining disks. In the drawings 60 there have been shown four of these setting elements or disks, one of which limits the driving shaft 2 to a single rotation while the other setting elements limit the driving shaft to two, three and four

rotations, respectively. For convenience in following the description these setting elements or disks have been designated on the drawings a^1 , a^2 , a^3 , and a^4 . The exponents indicate the number of operations or rotations of the shaft 2 contained in the cycle 70 determined by each of said setting disks. It will be obvious that any number of these setting disks may be employed, each predetermined a different number of rotations of the drive shaft. The setting disks are 75 loosely journaled upon the shaft 3 for independent oscillatory movement and are preferably separated or spaced one from the other by intermediate spacing sleeves 18. It will be obvious that other means of limiting 80 the lateral movement of the disks may be employed.

Extending transversely across the main frame 1 adjacent to the setting disks before mentioned is a stop bar 19 adapted to be engaged by a lug or projection 20 upon each of the disks. The stop lugs or projections 20 are differently located in relation with the stop bar 19 upon each of the disks. The stop lug 20 of the disk a^1 is removed from the 90 stop bar 19 a distance of one unit or step while that of the disk a^2 is spaced two units or steps from the stop bar, and the stop lugs of the remaining disks being spaced three and four units, respectively. Thus each of 95 the setting disks is capable of a different degree of oscillation before being arrested by engagement with the stop bar 19. The disks normally tend to move forward under the influence of individual motor springs 21, 100 there being one such spring for each disk. These motor springs 21 are coiled about the hubs of the disks with one end of the spring engaged beneath the stop bar 19 and the opposite end of the spring engaging a stud 22 105 projecting from the lateral face of the disk. The tendency of the spring is to rotate the disk forwardly to advance the stop lug 20 into engagement with the bar 19. The disk is held against rotary movement under the 110 influence of the spring by means of a detent or latch arm 23 which engages one of a series of ratchet teeth 24 upon the setting disk. In the drawing the teeth 24 are shown 115 formed in a separate plate 25 secured to the lateral face of the disk. The detent or latch arm 23 may be manually operated to release the selected timing disk by means of a key or oscillatory arm 27 shown at the right in Fig. 1; but is preferably disengaged by 120 means of an electromagnet 28. There is provided a separate detent or latch arm 23 for each timing disk and an electromagnet 28 for each detent. The electromagnets 28 are supported in a suitable manner upon the 125 transverse frame or supporting bar 29. Supported in suitable brackets 30 adjacent to the upper ends of the electromagnet 28 are the

armatures 31 adapted to be attracted by the corresponding electromagnets. The detent or latch arms 23 are carried by the armatures 31 whereby the attraction of an armature 31 will cause the disengagement of the 5 detent 23, carried thereby from the ratchet teeth 24. Upon such disengagement of the detent 23 the actuating spring 21 will immediately rotate the released disk until arrested 10 by the engagement of the stop lug 20 with the transverse bar 19. The degree of rotation of the setting disk is determined by the normal position of the stop lug 20 and this degree of rotation in turn determines the 15 number of rotations of the shaft 2 to be permitted. There is also formed upon each of the timing disks a cam 32. The said cams are alined one with the other when the disks are in their normal position. In the drawing 20 the cam 32 has been shown formed upon a separate plate attached to the lateral face of the disk. Pivotally supported upon a transverse shaft 33 mounted in the main frame 1 above the level of the shafts 2 and 3 25 is an oscillatory yoke or frame comprising parallel arms 34-34 supporting therebetween a roller 35 normally resting upon the peripheries of the timing disks adjacent to the cam faces 32 by which the roller is engaged and elevated upon the release of any 30 one of the timing disks. Extending rearwardly from the oscillatory swinging frame or yoke is a stop arm 36 having a laterally disposed nose 37, normally extending into the path of a shoulder 38 upon the lateral face of the clutch disk 10. The engagement of the stop arm 36 with shoulder 38 of the clutch disk normally locks the clutch disk against the advance movement and thereby 35 holds the clutch rollers 11 out of engagement with the driving head. Upon the oscillation of the yoke or frame by the elevation of the roller 35 under the influence of any one of the cam faces 32 upon the release of a timing 40 disk, the nose or lug 37 of the stop arm 36 is depressed, as shown in Fig. 4 and by dotted lines in Fig. 8 out of the path of shoulder 38, thereby releasing the clutch disk 10. Upon its release the clutch immediately advances under the influence of the springs 12 45 or 15, as before described, to cause the operative engagement of the clutch, thereby causing the shaft 2 to rotate in unison with the pulley. The shaft will continue to rotate in unison with the pulley 4 until the stop arm 36 50 is again elevated into the path of the shoulder 38 to arrest the rotation of the clutch disk 10 which will be thereby disengaged from the drive head 7. This is effected by returning the timing disks to normal position, thereby 55 permitting the stop arm to be elevated under the influence of the retracting spring 39, upon the return of cam 32 to normal. To return the timing disk from operated to nor- mal position the disks are provided with a 60 plurality of spurs or teeth 40 similar to the teeth of a spur gear or pinion. Carried upon the shaft 2 in planes common with the timing disks and adapted to engage the spurs of teeth 40 are fingers 41, one for each timing 65 disk. The construction is such that at each rotation of shaft 2 the finger 41 will pass in proximity to the timing disk and if the disk has been operated the finger engages a spur or tooth 40. By its camming gear action it 70 rotates the timing disk against the tension of its spring a distance of one unit or step. The detent or latch arm 23 is thus enabled to engage the next succeeding ratchet tooth 75 24 of the series to hold the disk in its ad- justed position. It is to be noted that the ratchet plate 25 and cam plate 32 are offset out of the plane of the teeth 40 whereby they 80 will not interfere with the resetting finger 41. In the event that timing disks a^2 , a^3 or a^4 have been operated, the corresponding finger 41 by engagement with the spurs or teeth 40 will return the disk a distance of one 85 step or unit at each rotation of the shaft 2. Upon the final return movement the cam 32 90 passes from beneath the roller 35, thereby permitting the frame or yoke to oscillate under the influence of the spring 39 to lift stop arm 36 into engaging position, thereby 95 disengaging the clutch from the shaft 2.

To insure the shaft 2 a full movement of its final rotation and to insure the final arrest of the shaft in exactly the same position after each operation and further to effect the restoring or tensioning of the 100 clutch springs 12 or 15 preparatory to the succeeding operation, there is provided upon the shaft a shoulder spiral cam 42 fixed to the shaft and rotating therewith. Loosely pivoted upon the shaft 3 is a lever 43 carrying a roller 44 which rides upon the periphery of the cam 42, as the latter rotates. The arm 43 is connected at its extremity to a spring 45 connected at its lower end to the main frame 1 which is tensioned by the elevation of the arm 43 under the influence of the spiral cam 42. The cam 42 is so timed upon the shaft that at the moment of the engagement of the stop arm 36 with the shoulder 38 and the consequent disengagement 105 of the clutch, the roller 44 will be passing onto the shoulder or offset of the spiral cam 42, as shown in Fig. 4. The shaft being at this moment disconnected from the pulley, the camming action of the roller 44 and the shoulder of the cam 42, under the influence of the spring 45, will give to the shaft 2 a slight additional movement as the roller 44 travels down the inclined shoulder 110 of the cam until the cam and shoulder assume the position shown by dotted lines in Fig. 5. This final movement of the shaft 2, 115 under the influence of the spring 45 acting

ing the cam, and means for restoring the cam by the operation of the main operating member.

4. In an apparatus of the character described, a main operating member, a normally disconnected driving member therefor, an intermittently operated clutch adapted to connect the driving and operating members, means controlling the operation of said clutch including a plurality of independently operated cam members each capable of a different degree of movement independently controlling the operation of the clutch, means for retaining said cam members in adjusted position, means for independently releasing said cam members at the will of the operator, and means for restoring the released cam member through a predetermined retrograde movement at each operation of the main operating member.

5. In an apparatus of the character described, a main operating member, a normally disconnected driving member therefor, an intermittently operated clutch adapted to connect the driving and operating members, means controlling the operation of said clutch including an oscillatory spring actuated cam disk controlling the clutch, a detent for the cam disk, means for retaining the cam disk in operated position, manually controlled means for releasing the cam disk, and interengaging means between the main operating member and the cam disk for actuating the cam disk through a retrograde movement at each operation of said main operating member.

6. In an apparatus of the character described, a main operating member, a normally disconnected driving member therefor, an intermittently operated clutch adapted to connect the driving and operating members, means controlling the operation of said clutch including an oscillatory spring actuated cam disk, a plurality of ratchet teeth on said disk, a detent engaging said ratchet teeth to hold the cam disk against the influence of its actuating spring, means to disengage the detent at the will of the operator a tooth or spur upon said disk for each unit of movement permitted said cam disk, and a finger operating in unison with the main operating member adapted to engage a tooth of the disk at each operation to restore said disk through one unit of movement.

7. In an apparatus of the character described, a main operating member, a normally disconnected driving member therefor, means controlling the engagement and disengagement of the driving and operating members, including a movable clutch member, a cam governing said movable clutch member, actuating means for the cam, a detent for the cam adapted to be disengaged at the will

of the operator, and means for intermittently operating the cam through a retrograde movement to normal position by the operation of said operating member.

8. In an apparatus of the character described, a main operating member, a normally disconnected driving member therefor, means controlling the engagement and disengagement of the driving and operating members, including a movable clutch member, a spring actuated oscillatory cam member governing the operation of the clutch member, a detent for the cam member disengaged at the will of the operator, means for arresting the oscillation of the cam member at the limit of the predetermined degree of movement, a plurality of teeth carried by the cam member, and an actuating member adapted to engage a succeeding tooth of the cam at each operation of the main operating member to restore the cam through a predetermined retrograde movement at each operation.

9. In an apparatus of the character described, a main operating member, a normally disconnected drive member therefor, a clutch adapted to intermittently connect the driving and operating members, and means governing said clutch including an oscillatory disk, a detent for said disk, means for disengaging the detent at the will of the operator, means for actuating the disk in one direction independent of the operation of the main operating member, means for returning the disk under the influence of the main operating member, and means for limiting the disk to a predetermined degree of movement.

10. In an apparatus of the character described, a main operating member, a normally disconnected drive member therefor, a clutch adapted to intermittently connect the driving and operating members, and means governing said clutch comprising a plurality of independently movable oscillatory disks, means for retaining the disks in normal inactive position, means for releasing any disk of the series at the will of the operator, means for actuating the disks in one direction independent of the main operating member, means to limit each disk to a different degree of movement, and means for returning the operated disk to normal position under the influence of the operating member.

11. In an apparatus of the character described, a driving member, a driven member, means intermittently engaging the driving and driven members, means for automatically releasing the driving and driven members at the termination of a predetermined number of operations, and means under the control of the operator for rendering the releasing means ineffectual.
